UNITED STATES PATENT OFFICE.

CHARLES T. McGEHEE, OF HOUSTON, TEXAS, ASSIGNOR OF ONE-HALF TO THE STANDARD RICE COMPANY, INC., OF HOUSTON, TEXAS, A CORPORATION OF TEXAS.

POLISHING MACHINE.

Application filed August 2, 1928. Serial No. 296,880.

This invention relates to new and useful improvements in a polishing machine.

One object of the invention is to provide a polishing machine particularly adapted for 5 polishing rice.

Another object of the invention is to provide a rice polishing machine which will effectively polish the grain after it has been passed through the huller and the hulls removed, said polishing machine being effective 10 to remove the dust from the grain and to polish the grain so as to give it a glossy appearance.

A still further feature of the invention is 15 to provide a rice polishing machine which will polish the grain with a minimum of breakage so as to produce a finished product with a higher percentage of whole grains than can be produced with polishing machines now in common use.

With the above and other objects in view, 20 the invention has particular relation to certain novel features of construction, operation and arrangement of parts, an example 25 of which is given in this specification and illustrated in the accompanying drawings wherein:—

Figure 1 shows a vertical sectional view of 30 a section of the machine showing a section of the screen removed.

Figure 2 shows a transverse sectional view taken on the line 2—2 of Figure 1.

Figure 3 shows an enlarged fragmentary 35 transverse sectional view, and

Figure 4 shows a transverse sectional view taken on the line 4—4 of Figure 1.

Referring now more particularly to the drawings, wherein like numerals of reference designate similar parts in each of the 40 figures, the numerals 1 and 2 designate upper and lower supporting members. Between these supporting members there is a vertically disposed cylindrical screen 3 formed of foraminated material. This screen is composed of a plurality of upright sections, each section being composed of a frame work formed of the marginal upright bars 4, 4, and the intermediate bar 5 connected by the upper 45 and lower arcuate ribs 6, 6 and the intermediate rib 7. The foraminated material of the drum 3 is fastened to the inner side of the frame sections of the frame so formed and the marginal bars 4 of each section are spaced from the corresponding bars of the adjacent 50 sections from top to bottom.

Supported on and secured to the supporting member 1 there is a bracket 8 having a central bearing 9 and there is a vertical shaft 10 disposed axially with respect to the screen 3 whose upper end works through the bearing 9. Secured to the upper end of the shaft there is a beveled gear wheel 11, which is in mesh with and driven by the pinion 12 which in turn is fixed on the inner end of the drive shaft 13 which rotates in the bearing 14 supported on the bracket 8. There is a drum 15 provided with the spiders 16 by means of which said drum is fastened onto the shaft 10. This drum is located within and is spaced from the screen 3 and is substantially equal in length to said screen. 70

Fastened to the outside of the drum are the flexible members 15, preferably formed of leather whose upper and lower ends are clamped to the drum by the surrounding bands 18, 18. These flexible members 17 consist of long strips and are so secured that their outer margins will be free. The upper and lower ends of the screen are open and fastened to the supporting member 2, beneath the screen there is a hopper 19 into which the polishing grain is delivered. Above the screw and aligned with the upper end thereof, there is an annular guide 20 which is secured to the upper supporting member 1 and whose lower margin is adjacent the upper end of the screen. The lower end of the screen is disposed adjacent the lower supporting member 2. 75

Fixed within the guide 21 and spaced therefrom there is a table 21. The grain is delivered onto this table from the chute 22. An annular ring 23 is fixed to the table 21 by means of the brackets 24 and is spaced above said table so as to provide a grain outlet 25 all the way around. Fixed on the shaft 10 are oppositely disposed paddle like arms 26 which sweeps around the upper surface of the table 21. These arms throw the grain outwardly, by centrifugal force, and cause the grain to accumulate against the rim 23 and gradually feed through the space 25 all the way around. 90

Between the respective sections of the screen are the grain baffles which will now be described. These baffles are of similar construction, and are illustrated in the Figure 3. A description of one will suffice for all. Each baffle comprises a channel having the outer wall board 27 and the side boards 28, 28 and 105

within the channel thus formed there is an anchor member 29 extending from end to end of the channel and faced with the facing 30 composed of rubber or other similar material. Externally threaded shafts 31, 31 are connected to the upper and lower ends of the anchor 29 and extend outwardly through the corresponding board 27, and have the nuts 32, 32, threaded thereon. These nuts are retained in place by the flange rings 33, 33, which are bolted to the board 27. The nuts 32 may be turned, to suitably adjust the grain baffles, by means of the grip members 34, and said nuts may be locked against movement by the lock nut 35 threaded onto the outer ends of the shafts 31. The side members 28 of the respective baffle channels are secured between the respective marginal bars 14 of the screen frame work by the bolts 36.

20 The grain baffles thus restrict the space between the screen 3 and the drum 15 and may be adjusted toward and from the drum 15 as described.

25 The grain is delivered onto the stationary table 21 and the drum 15 is rotated at relatively a high rate of speed, the paddle like arms revolving with it. The grain is thrown by centrifugal force outwardly against the ring 23 and is fed through the grain passage-way 25 all the way around and falls between the drum 15 and the screen 3. The rotation of the drum will carry the free margins of the friction members 17 outwardly and these friction members will hold the grain out 30 against the screen 3 during its downward course and will remove the dust therefrom and will polish the grain. The dust will pass outwardly through the screen and will be collected and disposed of in the conventional manner.

40 The friction members 17 will be held in close to the drum while passing under the grain baffles thus providing free spaces 37 into which the grain will be carried and in which said grain will accumulate the grain 45 then dropping between the drum and screen into the hopper for future disposition.

50 The grain will thus not be subjected to too severe friction by the operation of the friction members 17 and will not be swept entirely around the screen but will be confined between the grain baffles but will be held long enough to properly dust and polish the same. Consequently the grain will not 55 be unnecessarily broken by subjecting the same to a too severe polishing process.

60 While I have shown what I now consider the preferred form of the invention it is clear that mechanical changes may be made therein and equivalents substituted for the parts shown and I reserve the right to make such mechanical changes and substitutions as may be found desirable within the principle of the invention as defined by the appended claims.

What I claim is:—

1. A grain polishing machine including a cylindrical screen, a drum therein, flexible friction members on the outside of the drum, with their outer margins free, means for rotating the drum, means for feeding grain between the drum and screen and baffles disposed between the drum screen. 70

2. A grain polishing machine including a cylindrical screen, a drum therein, flexible friction members on the outside of the drum, with their outer margins free, means for rotating the drum means for feeding grain between the drum and screen and lengthwise baffles disposed between the drum screen, said 80 baffles being radially adjustable. 75

3. A grain polishing machine including a vertical cylindrical screen, a drum within and spaced from the screen and rotatable on an axis concentric with the screen, external friction members on the drum, means for rotating the drum, means for feeding the grain into the space between the screen and drum, and spaced vertical baffles between the screen 90 and drum. 85

4. A grain polishing machine including a vertical cylindrical screen, a drum within and spaced from the screen and rotatable on an axis concentric with the screen, external friction members on the drum, means for rotating the drum, means for feeding the grain into the space between the screen and drum, and spaced vertical baffles between the screen 95 and drum, said baffles being adjustable toward and from the drum. 100

5. A grain polishing machine including a cylindrical screen disposed with its longitudinal axis substantially vertical, a drum within and spaced from the screen and approximately concentric therewith external friction members on the drum, means for rotating the drum relative to the screen, means for feeding grain by gravity downwardly around the drum, longitudinal baffles spaced apart and disposed between the screen and drum, said baffles having yieldable inside faces. 105

6. A grain polishing machine including a cylindrical screen disposed with its longitudinal axis substantially vertical, a drum within and spaced from the screen and approximately concentric therewith, external friction members on the drum, means for rotating the drum relative to the screen, means for feeding grain by gravity downwardly around the drum, longitudinal baffles spaced apart and disposed between the screen and drum, said baffles having yieldable inside faces, and means for adjusting said baffles toward and from the drum. 115 120

7. A grain polishing machine including a vertical cylindrical screen, longitudinal baffles spaced apart and arranged on the inside of the screen, a rotatable drum in the screen and spaced therefrom and substantially con- 130

centric therewith, external friction means on the outside of the drum which cooperate with the screen.

8. A grain polishing machine including a vertical cylindrical screen, longitudinal baffles spaced apart and arranged on the inside of the screen, a rotatable drum in the screen and spaced therefrom and substantially con-

centric therewith, external friction means on the outside of the drum which cooperate 10 with the screen, and means for adjusting the baffles radially.

In testimony whereof I have signed my name to this specification.

CHARLES T. McGEHEE.
